(57) **CLAIM**

The ornamental design for a combined radio, alarm clock and light, as shown and described.

DESCRIPTION

FIG. 1 is a front perspective view of a combined radio, alarm clock and light showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the detail shown in FIG. 6. The broken lines in the drawings depict portions of the combined radio, alarm clock and light that form no part of the claimed design.

1 Claim, 9 Drawing Sheets
